UNITED STATES PATENT OFFICE.

JAMES SAMUEL FOLEY, OF LONDON, ENGLAND.

TYPE-WRITING MACHINE.

SPECIFICATION forming part of Letters Patent No. 511,416, dated December 26, 1893.

Application filed October 20, 1892. Serial No. 449,491. (No model.)

To all whom it may concern:

Be it known that I, JAMES SAMUEL FOLEY, a citizen of the United States, residing at London, England, have invented certain new and useful Improvements in Type-Writing Machines, of which the following is a specification.

This invention relates to type-writers and has for its object to simplify and reduce the cost of their construction and will be best understood by reference to the accompanying drawings, in which—

Figure 1 is a plan of a type-writer constructed according to this invention, parts of which, not necessary for a clear understanding of the invention, are for the sake of clearness omitted from this view. Fig. 2 a transverse section on the crooked line 2—2 of Fig. 1. Fig. 3 is a longitudinal section on the crooked line 3—3 of Fig. 2. Fig. 4 is an elevation of some of the type-levers as seen when looking in the direction of arrow 4 of Fig. 1. Fig. 5 is an end elevation showing the paper feeding device. Fig. 6 is a side elevation of one of the key-levers and its spring and a portion of the base-plate shown in section. Fig. 7 is a transverse section of the inking-pad drawn to an enlarged scale.

Like letters indicate like parts throughout the drawings.

A is the base-plate which may be supported on three or more legs or standards A' with blocks of rubber or equivalent material let into their lower ends in the usual manner.

B is the segmental plate to which are attached the brackets C in which the type-levers D are pivoted at d. This plate B hereinafter referred to as the top-plate, is secured to the base-plate A conveniently by three legs or standards b.

E is a segmental frame or hollow arc supported on preferably two standards e one at each side of the machine, secured at their lower ends to the top-plate B and in the hollow of which frame or hollow arc is located a pad E' for containing the necessary supply of ink. The inking pad E', as shown clearly in Fig. 7, may be composed of felt, or like absorbent material e' to hold the ink, faced with muslin, silk or other equivalent material e² upon which the type-heads rest and through which the ink passes.

According to the construction of the machine the pad may be modified but I find it convenient to place the pad in the hollow arc E and to hold the edges of the muslin or other covering e² with wires or a frame e³, which may be sprung into the arc. To supply the pad with ink this may be effected by brushing it over the outer surface of the covering e² or by removing the wires e³ and covering e² and applying it directly to the absorbent material e'. This form of pad serves efficiently to ink the type while keeping them out of contact with the felt which is a great desideratum because it is found that wherever the type is allowed to come into direct contact with felt or other similar absorbent inking material the type becomes clogged with fibers whereas according to this invention the covering e² is of such material or texture that it will allow of the ink passing through it but not any fibers of the absorbent material.

F are the key-levers which radiate from a common center and each of which, as shown in Fig. 6, is provided with a bearing point f which forms the pivot of the key-lever and is located in a conical recess a formed in the under side of the base-plate A. The recess a of each key-lever may be independent of the others or all the bearing points f may be located in one long groove of an angular shape in transverse section. Each key-lever is connected with one of the type-levers by a link f', passing through the plate A, and pin f² in the ordinary well-known manner, and each key-lever is moreover guided near its front end in a slotted segmental plate A² or between wires or equivalent guides.

G is a bar rigidly mounted in brackets G' secured to the under side or forming part of the base-plate A and on which bar G is pivoted the back end of the spacing lever G², which is preferably forked at its rear end as shown in Fig. 3, so as to pass on each side of the escapement mechanism. The front end of G² is provided with the usual finger plate g. Each key-lever F, as also the spacing lever G², is provided with a spring H (preferably formed of wire with a turn in it) for raising it to its normal position after it has been depressed by the operator, this spring being secured to the under side of the base plate A;

or any other suitable form of spring may be employed for this purpose. The bar G also forms the pivot of the lever I the front end of which is provided with the segmental plate I' which, with the lever I, is hereinafter referred to as the anchor I, and which segmental plate I' extends beneath the whole of the key-levers F and spacing lever G so that by the depression of any of these keys or the spacing lever, 10 the anchor I may also be depressed. The anchor I is pivoted by a pin j to a plate J the upper end of which carries the dogs or knife-edges of the escapement mechanism as hereinafter more particularly described.

15 Each type-lever D at its upper end has pivoted to it a shoe K to which is rigidly secured the type-head k which may have formed upon it three (as shown) or more or less type-faces k' k² k³ these type-heads k being so arranged 20 as regards the angle which they form to the respective shoes K that upon their depression for imprinting a letter they will always reach the platen with the type-faces presented in the proper position; this variation of the angle of the type-head k to the shoe K is most clearly shown in Fig. 4. Each shoe K is connected by a link L to the end C' of a joint-piece C' C² pivoted on a pin c in the appropriate bracket C. Each bracket C is provided 25 with a spring c' which bears upon the tail C² of the joint-piece C' C², and is adapted to yield sufficiently to allow of the movement of the joint-piece C' C² necessary for enabling the shoe K and lever D to move as one piece 30 after the shoe has fully engaged the lever D (as shown in dotted lines in the third position in Fig. 2) at which time something must yield, and I prefer this to be the link pivot, though a spring link would accomplish the 35 same purpose. The object of this temporary uniting of the shoe K with the lever D is to prevent the blurring of the impression upon the paper which can only be satisfactorily effected by the type striking and leaving the 40 paper after making the impression without the type partaking of the turning movement which it undergoes at other parts of its stroke.

45 M is the paper carriage in which the platen M' is mounted in the usual manner so that it 50 may be rotated by hand, for line spacing, by means of the milled head M², M³ being the pawl which by engaging with the tooth wheel M⁴ offers sufficient friction to prevent the platen being accidentally rotated.

55 N is the paper guide pivoted in any convenient manner to the paper carriage as for example on the spindle N' of the roller N² which is mounted in the frame of the paper carriage so as to bear with the necessary degree of pressure 60 against the periphery of the platen M'. n is a spring secured at one end to the paper carriage M and at its free end engaged with a pin m of the paper guide N so as to press said guide or the paper interposed between it and the platen M' against said platen; the upper surface of N may have en-

graved or otherwise depicted upon it, the usual scale.

m' are arms projecting from the back of the paper carriage M and between which is rigidly secured the bar M⁵ which is guided in its longitudinal motion in a slotted tube or guide O rigidly connected as by legs O' to the back part of the frame P which is adapted to slide in the direction from back to front of the machine or vice versa, in guides p secured to the base-plate A as shown most clearly in Fig. 3. By the provision of a slotted tube such as O for guiding the paper carriage said paper carriage is capable of traveling to an extent considerably greater than where no such guide is provided because no obstacle is presented to the passage of the arms m' along the slot or longitudinal passage of the guide; consequently were it not for other obstacles such as the arms S and escapement mechanism the carriage might readily be slipped endwise off the machine, but should this be necessary for repairing purposes or in order to replace the paper carriage by a longer or shorter one, it may readily be effected by detaching the obstructing parts. The slotted tube O may be made of any desired length and serves equally well to support a long or short paper carriage either of which may be used quite irrespective of the general dimensions of the rest of the machine excepting the escapement rack the length of which would vary with the length of the paper carriage.

The front part of the frame P has secured to it standards Q on the top of which is mounted the rail Q' over which travels the roller m² pivoted to the arm m³ extending downward from the rod m⁴ secured at its ends in the end plates of the paper carriage M. On the rod m⁴ are adjustably mounted the paper guides m⁵ m⁶ the upper end of the latter of which is pointed as shown in Figs. 1 and 3 to serve for indicating the position on the paper at which it is desired that the bell R should be struck or sounded, the block m⁷ of the paper guide m⁶ for this purpose being provided with the pivoted bell-trip m⁸ and stop pin m⁹ the former of which by abutting against the arm r secured to the spindle r' of the bell-hammer r² causes said hammer to be depressed so that when the trip m⁸ passes beyond the arm r the hammer r² will be immediately raised by the spring r³ encircling its spindle r' and will strike the bell R. The bell-trip m⁸ is so arranged that in its return movement on coming into contact with the arm r it will be turned on its pivot to enable it to pass over said arm without operating it. By reason of the leverage exerted through the bell-trip m⁸ and pin m⁹ the block m⁷ is clamped upon the rod m⁴ at the time it is pressed against the bell-arm r for sounding the bell.

At the under side of the paper carriage M is supported, by preferably two bracket arms S, the escapement rack S' which is provided with two sets of teeth one s at its upper edge

and the other s' at its lower edge and both facing in the same direction; or instead of one bar S' with two sets of rack teeth formed upon it, each set of teeth $s\ s'$ may be on a separate bar. The before described plate J which is guided so that it may freely reciprocate in a vertical direction has secured to its upper part the dog or knife-edge j' adapted to engage with the rack teeth s at each depression of a key-lever or the spacing lever.

The plate J has also hinged to it a bracket or frame j^2 carrying at its upper part a dog or knife-edge j^3 . The frame j^2 is pivoted to J at j^4 and is provided at its lower part with a spring j^5 which tends always to throw the bracket j^2 and dog or knife-edge j^3 away from the plate J .

T is a rod guided in the supporting bracket T' and connected at one end with the movable knife-edge j^3 , its other end terminating in a loop or equivalent handle t so that the knife-edge j^3 may be readily pushed into the position shown in dotted lines in Fig. 3 in which it is out of engagement with the rack s' . t' is a collar secured on the rod T for limiting its outward movement by abutting against the bracket T' .

To one of the arms S is secured an arm U the downwardly projecting portion of which (Figs. 2 and 5) serves for the attachment to the carriage M of one end of the flexible band, chain or equivalent u the other end of which is secured to the barrel U' containing the spring by which the carriage is drawn along. This barrel is mounted on a spindle u' secured to the adjustable frame P and at its lower part is provided with the usual ratchet wheel u^2 with which engages the pawl u^3 for preventing the unwinding of the spring contained in the barrel.

At the front part of the frame P is provided a nut p' integral therewith and into which is screwed the back end of the rod V which is guided so that it may move freely in the direction of its length through a bracket or post v secured to or forming part of the base-plate A . The rod V is encircled by the spring v' which exerts its pressure between the post v and a collar v^2 rigidly secured on the front end of the rod V so as to tend always to draw the frame P forward, a collar v^3 adjustable on the rod V serving to limit the extent to which the frame P may be moved in a forward direction.

To the middle one of the legs or standards b supporting the top plate B is pivoted a bent or bell-crank lever $W\ W'$ the end of the arm W of which is provided with a finger-plate w and the end of the arm W' of which is pivoted at w' to a bar w^2 which bears against the front of the frame P this bar w being guided in the block w^3 so that it may move freely only in the direction of its length. To the arm W of lever $W\ W'$ is pivoted the catch arm X which is provided with say two teeth $x\ x'$ which are adapted to engage with the shoulder or face x^4 for holding

the paper carriage in the proper relative positions necessary for the printing of one or other of the sets of type-faces $k'\ k^2\ k^3$ as hereinafter more fully described. The teeth $x\ x'$ of arm X are pressed into engagement with the shoulder x^4 by means of a spring x^2 secured on the arm W of lever $W\ W'$ and may be disengaged from x^4 by the operator pressing on the cross-bar x^3 secured to the catch arm X .

Y is a frame formed on the end of an arm y rigidly secured to the top plate B and y' is a rod secured at its lower end to the arm y and at its upper end passing through the segmental frame E and screwed and provided with a nut y^2 . This arrangement of the arm $y\ y'\ y^2$ enables the vertical position of the frame Y to be adjusted and supports it against depression. The opening in the frame Y is such as will accommodate the type heads k and secure them in position at the moment of striking the paper as shown in dotted lines in Fig. 2, and the gap y^3 in one side of the frame Y is provided for the purpose of enabling the last printed matter to be readily seen.

Each type-bar of the before described apparatus is adapted for printing three letters or symbols for each of which the paper carriage is moved into the appropriate position for receiving the particular letter by the operation of the lever $W\ W'$. For example when the carriage M is in its rearmost position and the tooth x engages the shoulder x^4 as shown in Fig. 2 the type-face k' will be that which by each depression of a keylever is brought into contact with the platen M' or paper thereon; if the paper carriage occupies its intermediate position, that is when the tooth x' engages the shoulder x^4 , then the type-face k^2 will be that brought into position for printing, and when the paper carriage is in its foremost position when neither of the teeth $x\ x'$ engage with x^4 then the type-face k^3 will be brought into operation. The three positions, which the lever $W\ W'$ occupies for causing the shifting of the paper carriage for the printing of either of these sets of type-faces, are indicated in Fig. 2, one in full lines and the other two in dotted lines. A convenient arrangement of the type-faces on the type-heads k is that the type-faces k' should print capitals, the type-faces k^2 small letters and type faces k^3 numbers, but it will be obvious that any other arrangement of letters or symbols on the type-heads k may be provided for.

When it is desired to operate the machine the paper is introduced between the roller N^2 and platen M' . The platen is then rotated by means of the milled head M^2 in the direction indicated by the arrow in Fig. 2 so that the paper passes around the platen and between it and the paper guides $M^5\ M^6$, and when the edge first introduced is in proper position it is passed beneath the paper guide N which is drawn back for this purpose in the usual manner. Supposing now that it is desired to commence

with a capital letter:—For this purpose the paper carriage M must occupy its rearmost position as shown in Fig. 2, the catch arm X and lever W W' also occupying the positions shown in full lines in that figure. The necessary key-lever for imprinting the required capital is then depressed and the type-face k' will be brought on to the paper for imprinting that letter, and so on. Should it be required to continue with the printing of capital letters the necessary key-levers are depressed in proper succession while the arm W of lever W W' still occupies its lowest position. Should it now be desired to print with small letters, it will be necessary to depress the catch arm X by means of the cross-bar x³ to disengage x from x⁴ and allow the arm W of lever W W' to be raised by the pressure of the spring v' until by the spring x² the tooth x' of arm X is engaged with x⁴, at which juncture the paper carriage will be in its intermediate position having been drawn into that position from its rearmost position by the spring v'. In this intermediate position the center of the platen M' is directly beneath the point at which the type-faces k² meet it so that these type-faces only print upon the paper, the type-faces k' and k³ standing away free from the paper on either side of the point of contact of the type-face k² with the paper. Should it now be desired to print with numbers the catch arm X is again depressed so as to disengage x' from x⁴ and the arm W of lever W W' is allowed to assume its highest position the spring v' while moving it to this position also drawing the paper carriage M into its foremost position, so that the center of the platen is brought immediately beneath the point at which the type-face k³ strikes the paper the result being that only the symbol depicted on this type-face will be printed on the paper, the other two type-faces k' k² standing clear of the paper. At each operation of a key-lever the appropriate type-head k and shoe K are moved from the position which they relatively occupy to the type-lever D shown in full lines in Fig. 2 to that shown in dotted lines at the part where it strikes the paper, an intermediate point of this reversal of position being shown also in dotted lines in Fig. 2. When the type head k is in the position shown in full lines in Fig. 2, the type-faces k' k² k³ receive from the pad e' the necessary ink for printing and it will be seen that whereas in this position the type-faces k' k² k³ are turned away from the platen M' yet by the link L the shoe K, during the descent of the type-lever D, is caused to turn upon the pivot z so that the type-faces are gradually turned over to the descending side of the type-lever D and are in proper printing position when the type-lever D is at or nearly at the lowest point of the stroke. At each descent of a key-lever or upon the spacing lever G² being depressed the anchor I is also depressed, this resulting also in the depression of the plate J. At each depression

of the plate J the spring-controlled dog or knife-edge j³ is lowered out of engagement with the rack teeth s' and the fixed dog or knife-edge j' is lowered into engagement with the rack teeth s. Immediately upon the release of the knife edge j³ from s', the said knife-edge is forced by its spring j⁵ to assume the position shown in dotted lines in Fig. 3, so that when the key-lever F or spacing lever G² is next released and raised by its appropriate spring H and the anchor I and plate J are raised by their spring j⁶, the knife-edge j³ which, before its last descent was in engagement with one tooth, will engage with the next tooth, the carriage being drawn forward by the spring in barrel U' to the extent of the width of this tooth until it is stopped by the knife-edge j³ abutting against the plate J. The width of each tooth corresponds with the amount of movement to be imparted to the carriage for each symbol. Should it be desired to move the carriage toward one or other side of the machine without printing or resorting to the use of the spacing lever G² this may be speedily effected by pushing the handle t in the direction indicated by the arrow in Fig. 3 which will have the effect of pushing the dog or knife-edge j³ into the position shown in dotted lines in Fig. 3 when it will be quite clear of the rack teeth s' and the knife edge j' being in its raised position and consequently out of engagement with the rack teeth s the carriage may be moved freely in either direction. For line spacing the platen is turned to the required extent by means of the milled head M² as will be well understood.

The before described apparatus may be modified without departing from the spirit of the invention. For example as will be obvious, the type-heads k instead of having three letters upon them may each be provided with more or less than that number, the frame P and paper carriage M being adjustable to a corresponding number of positions.

I claim—

1. In a type-writer the combination with a type-lever D bracket C, shoe K, joint-piece C' C², and link L, of a spring such as c' bearing upon the joint-piece C' C² substantially as described and illustrated in the accompanying drawings.

2. In a typewriter the combination with a paper carriage M and movable frame such as P on which it is mounted, of a lever such as W W', rod such as w², and spring controlled rod such as V substantially as described and illustrated in the accompanying drawings.

3. In an inking pad for type-writers the combination with the absorbent material e' and face or covering such as e² of wires or a frame such as e³ substantially as described and illustrated in the accompanying drawings.

4. In a typewriting machine, the combination of the carriage, the type levers and their pivoted shoes, two sets of rack teeth, the spring-controlled plate J, carrying dogs or

knife edges j' , j^3 , the latter movable in relation to the said plate, and the rod T, for releasing said dog j^3 , from the lower set of rack teeth, substantially as shown and in the manner set forth.

5. In a typewriting machine, an inking-pad consisting of an arc-shaped frame having a lining of absorbent material, provided with a facing or covering, and a suitable holder fitting within said arc-shaped frame and maintaining the absorbent material and its cover in place, substantially as shown and for the purpose set forth.

6. In a typewriting machine, the combination of the lever W, W', the notched arm X, and movable frame P, supporting the carriage, and intermediate devices for automatically

adjusting said frame forwardly on depression of said lever, substantially as described.

7. In a typewriting machine, the combination of the lever W, W', the notched arm X, and spring x^3 , the movable frame P supporting the carriage, the bar bearing against said frame and pivoted to an arm of said lever, and the spring-actuated rod V adjustably connected to the frame, substantially as described.

In testimony whereof I have hereto set my hand in the presence of the two subscribing witnesses.

JAMES SAMUEL FOLEY.
